FONT OF NUMERALS

Henri Edmond Vermot, Lancaster Township, Pa.,
assignor to Hamilton Watch Company, Lancaster, Pa.

Application July 25, 1951, Serial No. 16,011

Term of patent 3½ years

(CL. D64—12)

To all whom it may concern:

Be it known that I, Henri Edmond Vermot, a citizen of the United States, residing in the township of Lancaster, State of Pennsylvania, have invented a new, original, and ornamental Design for a Font of Numerals, of which the following is a specification, reference being had to the accompanying drawing, forming a part hereof.

The drawing illustrates face views, slightly in perspective, of a font of numerals, showing my new design.

I claim:

The ornamental design for a font of numerals, as shown.

HENRI EDMOND VERMOT.
